ABSTRACT OF THE DISCLOSURE

In manufacturing lightweight precast concrete structural components having two predominant densities, a stiff mix of appropriate viscosity of spherical aggregate of substantially uniform size and a matrix material consisting of fine gritty material, cement and water is formed. The proportions of the spherical aggregate and the matrix material in the stiff mix are such that the total volume of the matrix material is substantially less than the volume of voids between the spherical aggregate when measured alone. The mix is then placed in a mold and vibrated so as to distribute the matrix to coat all of the spherical aggregate and to fill the voids in the lower portion of the mold thereby forming a structural component having a solid lower portion and a porous upper portion. The component is then removed from the mold and can be used.

The invention relates to a method for forming precast concrete structural components, particularly but not exclusively to precast floor beams and slabs, while the object of the invention is to provide a method for forming precast floor beams and slabs which are light in weight in comparison with their strength.

It is common knowledge that in a simple reinforced concrete beam designed to be subjected to loads acting vertically downwards, the concrete above the neutral axis is subjected to compressive forces, which forces the concrete is suitable to resist, and that below the neutral axis the beam is subjected to tensional forces which concrete alone is not suitable to resist and that steel reinforcement is provided to resist the tensional forces.

It is known to provide reinforced concrete beams in which the cross section area of the concrete below the neutral axis is substantially less than the area of concrete above the neutral axis, the concrete being of the same consistency throughout, thereby to economize in the volume of concrete used and to reduce the weight of the beams without substantially affecting the strength of the beams.

It is now proposed in accordance with the present invention to produce precast concrete beams, slabs and other structural components in which the density of the concrete is different in different parts of the components, that part of the component being subjected under load to compressive forces being of dense concrete while the parts not so subjected are of a less dense nature.

It is proposed in accordance with the invention to make use of a particular property of uniform spherical aggregate. Such aggregate can be natural, but is rarely found sufficiently spherical and uniform in shape, and it is therefore preferred to use a manufactured spherical aggregate such as pellets of clay, shale or like argillaceous materials which have been rendered spherical and baked, such as known by the name "Argilag" R.T.M.

If a stiff mix of appropriate viscosity is made with a uniform spherical aggregate of substantially uniform size,

2

a fine gritty material, such for example as sand, fly ash or crushed natural or manufactured mineral material, cement and water, in which the total volume of the matrix is less than that of the voids in the aggregate measured alone, it is possible to vibrate the mix in the mould for the structural component so that the lower part becomes solid while the upper part becomes porous. If the component is a floor beam the solid part is required above the neutral axis and therefore the beam is moulded upsidedown.

With aggregates of the type mentioned, and with vibration of suitable amplitude, frequency and duration, it is possible to produce concrete components with the desired proportion of solid and porous parts, depending upon the ratio of the quantity of matrix used to the quantity required to completely fill all the voids in the aggregate. Concrete of this sort can be made with very high compressive strength in the solid part and very much lower strength, modulus of elasticity and weight in the porous part.

The technique proposed above presents no difficulties in the manufacture of concrete components on a large scale.

The invention consists in a method of manufacture of precast concrete structural components such as floor beams and slabs, comprising preparing a stiff mix of appropriate

viscosity of spherical aggregate of substantially uniform size, fine gritty material, cement and water in such proportions that the total volume of the matrix is substantially less than the volume of the voids in the aggregate when measured alone, placing the mix in a mould of the shape of the component to be manufactured, vibrating the mix in the mould at a suitable amplitude, frequency and duration as will distribute the matrix in the required location within the interstices in the aggregate under the action of gravity.

The invention further consists in a method of manufacture of precast concrete structural components as set forth in the preceding paragraph in which the vibration of the mix is carried out for such duration that the concrete at the bottom of the mould is dense and without voids while the concrete at the top of the mould is porous.

In one method of manufacture in accordance with the invention it is proposed to cast beams in moulds with a smooth flat bottom plate, with the main reinforcement secured in the upper part of the mould. There may be provided in the lower part of the mould light reinforcement solely for the purpose of making the beams safe against breakage in handling. When the beams are finished the lower part in the mould is the dense part and the beams are therefore installed with this part uppermost, so that it forms the compressive zone above the neutral axis.

The accompanying drawing shows diagrammatically, by way of example only, the precast aggregate component in the course of manufacture in which,

FIGURE 1 is a cross section through a mould filled with the mix before it is vibrated,

FIGURE 2 is a cross section of the same mould after the mix has been vibrated,

FIGURE 3 is an enlarged part-section showing the relationship between the aggregate, and the cement before it is vibrated, while,

FIGURE 4 is an enlarged part section showing the relationship between the aggregate of the cement after the mix has been vibrated.

The mould shown in FIGURES 1 and 2 has side wall portions 1 and 2 which stand upon a flat bottom plate 3, while the main reinforcement parts 4 are secured in position as shown, by any known convenient method. At the same time that the mix is placed in the mould, the solid matter and the voids will be distributed in random manner throughout the mould as represented by the cross hatching of average density.

After the mix has been vibrated at a suitable amplitude and frequency, and for a suitable duration, the mix will sink in the mould and all voids in the lower part of the mould will be filled and only that part towards the upper part of the mould will contain voids, as shown in FIGURE 2 and represented by the dense and light cross hatching respectively.

During the process of mixing the concrete all the spherical aggregate is wetted by the cement and when first placed in the mould a superfluity of the cement and sand is positioned in places such as indicated at 5 in FIGURE 3 while the spherical aggregate in other places such as at 6 is in contact and has a thin coating all over with additional cement around the points of contact, held there by surface tension.

When the mould has been fully vibrated the excess cement falls to the bottom of the mould and fills the voids as at 7 up to a predetermined level, while above this level the whole of the concrete is provided with voids.

The main function of the porous part of the beam is to support and locate the main reinforcement. Depending upon the duty the beam has to perform the solid part might generally constitute one fifth or less of the total depth of the beam.

One advantage of manufacturing beams in the proposed manner is that they can be supplied to the building site and be laid to form a floor with a smooth and flat upper surface and thus avoid the necessity of laying a screeding thereon. Floor beams may be about twelve inches wide and little difficulty is experienced in laying them side by side to provide a level, smooth surface over any required area and where the joints between the beams are filled with a suitable cement and sand mix.

The edges of the beams in the porous area may be so shaped that, when forced together, a concentrated load on one beam may be transferred to the adjacent beam.

If desired the beams may be made of such sections that channels are left in the upper surface of the floor between adjacent beams for the accommodation of electric conduits and the like, and since the concrete forming the lower layers of the floor is comparatively soft, holes may be punched through where necessary for electrical outlets.

The tensile strength of the porous part of the component may be increased by the addition of fibrous material of a mineral character to the mix or a binding emulsion may be added to the cement if desired to increase its tensile strength.

It is also within the scope of the invention to manufacture panels which may be used as wall panels having an external solid face which is impermeable while the inner porous face provides insulation against heat loss. Such panels can be substituted with advantage for cavity walls and the external face can be provided with any desired finish.

Only beams, slabs and panels have been referred to hereinbefore, but it is to be understood that precast concrete components of other forms may be constructed in accordance with the present invention.

I claim:

1. A method of manufacturing lightweight precast concrete structural components such as beams and slabs comprising the steps of introducing spherical aggregate of substantially uniform size and matrix material consisting of fine gritty material, cement and water to form a stiff mix, said mix having proportions of said spherical aggregate and said matrix material such that the total volume of said matrix material is substantially less than the volume of voids between said spherical aggregate when measured alone; placing said stiff mix in a mold defining the particular structural component being cast; vibrating said stiff mix in said mold at a predetermined amplitude, frequency and duration as will distribute said matrix to coat all of said spherical aggregate, uniformly distribute said spherical aggregate in said mold, and fill in the voids between said distributed spherical aggregate in the lower portion of said mold thereby forming a solid lower portion and a porous upper portion; and removing the so formed structural component from said mold.

2. A method of manufacture as claimed in claim 1 in which said spherical aggregate is of the manufactured kind.
